DRUM TYPE SPRAY DRYER

Robert Feix, Frankfurt am Main, Germany

Application June 17, 1954, Serial No. 437,479

3 Claims. (Cl. 34—57)

This invention relates to spray drying, and more particularly to methods and apparatus especially adapted for spray drying powdered fruit, powdered vegetable, pulverulent chemicals and the like.

It is an object of this invention to provide a spray dryer capable of continuous operation.

Another object of the invention is to provide an improved, drum type spray drying apparatus designed for continuous operation and effecting a substantially immediate drying of the wet material, at relatively very low temperatures.

A still further object of the invention is to provide a method and apparatus for spray drying foodstuffs sufficiently rapidly as to avoid any detrimental influence on color, aroma or vitamin content of the foodstuffs.

Other objects, and the manner in which the same are attained, will become apparent as this specification proceeds.

In the manufacture of dried products, the starting material quite often is a wet material which owing to various causes, is rendered plastic in the course of the drying procedure and thus becomes difficult to treat in the drying apparatus. This plasticity may be caused, for example, by the low melting temperature of some kind of sugar which may be present, because of slow crystallization etc. A temporary plasticity, however, impedes the conveyance of the material in the dryer. While it is true that dryers, even of the spray drying type, have been proposed heretofore which can handle material of the kind described above, these prior devices suffer from the drawback that they must be stopped for discharge purposes, thus involving loss of time and interruption of the operation. This stoppage, moreover, has a detrimental influence on the dried material a good part of which, quite frequently, sticks to the walls to remain there until it is removed therefrom mechanically, and more often than not manually, which results in a lengthened exposure to the drying temperature of 80-100° C. and in a detrimental change in the properties of the material. Powdered fruit and vegetable products, as well as many chemicals, are particularly susceptible to being damaged in this manner.

The invention contemplates a drum type spray dryer designed for continuous and uniform operation wherein the material is protected during treatment and drying is effected substantially immediately and at such low temperatures as from 45 to 50° C., thus involving a material saving in the heat supply. Evaporation takes place, as it did heretofore, in a warm air eddy current which does not require the high temperatures used in other dryers, including roller dryers. Drying is effected immediately, i. e. in about half a second, so any change in color or aroma, or any detrimental influence on vitamins etc. is avoided. The invention contemplates further that the drying zone is followed by a cooling zone wherein the material under treatment is rendered pulverulent to prepare it for an equally continuous discharge from the drying apparatus. This cooling zone permits converting

2

even those products which on drying have become plastic, into a more or less easily pulverizable state so they can be conveyed further by means of discharge devices, in a continuous operation. This is important also where crystallization problems are concerned inasmuch as a rapid and continuous operation is a prerequisite for retaining the aroma, the added sugar and the vitamins in powdered fruit, for example. Given a slow rotation of the drying drum at a rate of from about 4 to about 15 revolutions per hour, the complete operation takes only a few minutes or at most 1/4 hour, most if not all of the actual drying in the air current taking up but fractions of a second. The cooling zone may be equipped with a water or air cooling system, and even an interior air cooling system may be employed if the material has passed beyond the spraying range.

For carrying out the method according to the invention, a drum type dryer is contemplated which is provided with inlet conduits for the wet material and the warm air which conduits may extend through the axle journal of the rotary drum. In the interior of the closed rotary drum, these combined conduits terminate in a unit comprising a spraying nozzle for the wet material and surrounding the same, an inlet for the warm air, which unit is eccentrically disposed in the cylindrical drying chamber inside the drum. This arrangement yields the largest possible spraying cone, i. e. the largest possible effective drying space.

In the drawing attached to this specification and forming part thereof, one embodiment of an apparatus according to the invention is shown diagrammatically by way of example.

In the drawing,

Fig. 1 is a front view (partly in section) of the spray drying drum of the invention;

Fig. 2 is a side view (partly in section) of the spray dryer shown in Fig. 1, and

Fig. 3 is a plan view (partly in section) of the spray drying apparatus shown in Figs. 1 and 2.

Referring now to the drawing wherein like reference numerals denote identical elements, a stationary standard 1 mounts for rotation, the drying drum 2 which carries a ring gear 3 driven by a drive gear 4. When the drive applies on the periphery, as shown in the drawing, a saving in power results; however, a direct drive of the axle is also possible with a closed drum. The drum 2 may also be equipped with stationary walls and an open drum cylinder revolving therebetween. In view of the cooling system required, however, a closed cylinder is preferred. The drum 2, as shown in the drawing, is provided with circumferential rails 5 by means of which it is supported on bearing rolls 6. Where the walls of the drum revolve, as shown in the drawing, the warm air supply conduit 7 and the wet material supply conduit 8 surrounded thereby, extend into the interior of the drum through the axle journal or shaft A of the drum. Both supply conduits proceed from the point of entry into the drum interior, along a curved path to the inlet openings 9 and 10 which are disposed eccentrically to the shaft A of the drum, opening 9 being provided in the form of a spraying nozzle or disk designed to spray the wet material into the warm air eddy current, in the direction of the drum diameter so the material under treatment is thrown against the wall of the drum, over the range of the spraying cone 14.

Intermediate the wall of the drum and the unit comprising spraying nozzle 9 and warm air supply 10, an arched stationary partition 11 is arranged which is located near the wall of the drum and is designed to control the air eddies. This partition serves the purpose of separating the drying chamber proper with its supply of

warm air, from the cooling chamber. Any powder particles which in small quantity, may stick to this partition, are removed from time to time by a stripping device so they will drop on the wall of the drum to be removed with the bulk of the dried material. The cooling zone situated behind the partition may be equipped with any known type of cooling system. Cooling by a few degrees only is sufficient to obtain the effect desired. As shown in the drawing, the stripping device may be provided in the form of stripping members 12 which are mounted on the partition 11. Both the partition 11 and the stripping members 12 are stationary and do not take part in the revolution of the drum 2; as shown in the drawing, the partition 11 may be mounted on the conduits 7 and 8 which are also stationary and do not rotate with the drum. The stripping members 12 are designed to convey the dried material to a lock or discharge opening 13 (Fig. 1) through which it is removed from the apparatus. The wet air is drawn off through an exhaust pipe 15, to be passed through a wet air filter (not shown) if desired.

The spray drying method according to the invention proceeds as follows. The wet material is conveyed under pressure, through the conduit 8 to the nozzle 9, while at the same time warm air is passed through the conduit 7 to the opening 10. The wet material sprayed from the spraying nozzle 9 is met by the warm air eddy current and is distributed over the spraying range 14 to be dried substantially immediately, the quantity of dried material adhering to the wall of the drum depending on the tendency of the material under treatment to be rendered plastic under the conditions of treatment. Revolution of the drum, however, causes the dried material to pass rapidly into the cooling zone located in back of the partition 11 where it is rendered pulverizable. The stripping members 12 push the dried material, the bulk of which is a powder, against the front wall toward the discharge opening 13. The wet air is drawn off through the exhaust pipe 15.

If stationary front walls are provided for the drum 2, the supply conduits for the wet material and the heated air can be introduced therethrough directly, eccentrically to the axis of the drum.

I wish it to be understood that I do not desire to be limited to the exact details of construction, design, operation and procedure shown and described as modifications within the scope of the appended claims may occur to a person skilled in the art which involve no departure from

the spirit of the invention nor any sacrifice of the advantages thereof.

I claim:

1. Spray drying apparatus comprising a rotary drum, means for rotating said drum, exit means in the wall of the drum for removal of material, a supply conduit for wet material extending into said drum, a supply conduit for heated gas concentric with the wet material supply conduit, both conduits terminating in openings eccentric to the axis of the drum, and a stationary partition located in proximity to the drum wall and on the side nearest the conduit openings, said partition subdividing the interior of the drum into a drying chamber and a cooling chamber.

2. Spray drying apparatus comprising a rotary drum, means for rotating said drum, exit means in the wall of the drum for removal of material, a supply conduit for wet material extending into said drum and having a spraying nozzle on its opening, a supply conduit for heated gas concentric with the wet material supply conduit, the terminal openings of both conduits being eccentric to the axis of the drum, and a stationary partition located in proximity to the drum wall and on the side nearest the conduit openings, said partition subdividing the interior of the drum into a drying chamber and a cooling chamber.

3. Spray drying apparatus comprising a rotary drum, means for rotating said drum, exit means in the wall of the drum for removal of material, a supply conduit for wet material extending into said drum and having a spraying nozzle on its opening, a supply conduit for heated gas concentric with the wet material supply conduit and terminating in a heated gas outlet surrounding said spraying nozzle, the terminal openings of both conduits being eccentric to the axis of the drum, and a stationary partition located in proximity to the drum wall and on the side nearest the conduit openings, said partition subdividing the interior of the drum into a drying chamber and a cooling chamber.
